TRANSFORMER MOUNTING

Wayne H. Gilman, Oak Park, Ill., assignor to
 Permoflux Corporation, Chicago, Ill., a corpora-
 tion of Illinois

Application September 27, 1946, Serial No. 699,921

5 Claims. (Cl. 175—356)

1

This invention relates to mounting of trans-
 formers in their position of use, as for example
 upon the yoke of a loud speaker or the like.

In the manufacture of loud speakers for use
 in radios or public address systems it is cus-
 tomary to permanently associate an impedance
 matching transformer with the speaker as by
 mounting the transformer upon the magnetic
 yoke of the speaker. Such transformers are
 usually manufactured with a mounting frame in
 the form of a channel-shaped member that em-
 braces three sides of the rectangular pack of
 laminations of the transformer in such a way
 that the free ends of the mounting frame project
 beyond the other edge or side of the laminations
 to afford ears for use in securing the trans-
 former in position on the speaker yoke. The mount-
 ing frame of the transformer is formed by notching
 the side flanges of a channel member and
 bending the web of the channel to afford the
 desired three-sided frame, and at the ends of
 the channel where the projecting ears are formed,
 the flanges of the channel are cut away so that
 the fastening of the ears to a cooperating mount-
 ing means is facilitated. Such cooperating
 mounting means usually take the form of a flat
 rectangular plate, fixed as by welding to the yoke
 of the speaker, and against which the exposed side
 of the laminations is positioned when the trans-
 former is finally mounted. The mounting plate
 has been provided with narrow projecting lugs
 centrally disposed on opposite ends thereof in
 position to be extended through and interlocked
 with transverse slots formed in the respective
 ears of the mounting frame. In thus mounting
 the transformer it has been necessary to bend
 one or both of the side members away from the
 laminations in order to enable the lugs of the
 mounting plate to pass through the slots in the
 respective ears of the mounting frame, and after
 bending the frame back into position with the
 lugs passing through the slots, it has been cus-
 tomary to bend the lugs so as to engage the outer
 faces of the ears, thereby to lock the sides of the
 frame in position. Such mounting of a trans-
 former in position on the yoke of a loud speaker
 has been considered to be objectionable, pri-
 marily because of the uncertainties that are in-
 troduced by reason of the required outward bend-
 ing and disturbance of the sides of the mounting
 frame. It will be recognized that transformers
 that are used for matching purposes must have
 predetermined electrical characteristics, and such
 transformers are normally manufactured and
 tested by companies that specialize in trans-

2

former work. Thus, the electrical characteris-
 tics of the transformer are determined and tested
 while the mounting frame is in place on the
 transformer, and when it becomes necessary to
 disturb the relationship of this metallic mounting
 frame with respect to the laminations of the
 transformer, there is danger that the electrical
 characteristics of the transformer may be objec-
 tionably modified. It is, therefore, an important
 10 object of the present invention to enable trans-
 formers to be mounted in position on the yoke
 of the loud speaker without disturbing the re-
 lationship of the mounting frame to the lamina-
 tions of the transformer, and a related and more
 15 specific object of the invention is to enable such
 mounting to be simplified so as to eliminate man-
 ual operations that have heretofore been re-
 quired. A further object of the invention is to
 enable such transformers to be mounted in posi-
 20 tion and fixed in such position by operations that
 involve bending of only those parts of the mount-
 ing frame which are not in contact with the lam-
 inations of the transformer. More specifically,
 25 it is an object of the present invention to enable
 such a transformer to be quickly moved into the
 desired position with relation to the yoke of the
 transformer and to enable the transformer to be
 30 fixed in position readily and easily and without
 disturbance of the relationship of the mounting
 frame with respect to the laminations of the
 transformer.

Other and further objects of the present in-
 vention will be apparent from the following de-
 35 scription and claims and are illustrated in the
 accompanying drawings which by way of illustra-
 tion, show a preferred embodiment of the present
 invention and the principle thereof and what I
 now consider to be the best mode in which I
 40 have contemplated applying that principle.
 Other embodiments of the invention embodying
 the same or equivalent principles may be used
 and structural changes may be made as desired
 by those skilled in the art without departing from
 45 the present invention and the purview of the
 appended claims.

In the drawings:

Fig. 1 is a perspective view of a transformer
 mounted in accordance with the present inven-
 50 tion;

Fig. 2 is a perspective view showing the trans-
 former and the mounting bracket in the relation
 in which they are disposed just prior to assembly;

Fig. 3 is a fragmentary side elevational view of
 55 the assembly;

Fig. 4 is a sectional view taken along the line 4—4 of Fig. 3; and

Fig. 5 is a fragmentary sectional view taken along the line 5—5 of Fig. 2.

In the form chosen for disclosure herein, the invention is illustrated as embodied in the mounting of a transformer 10 in fixed position on a yoke 11 of a loud speaker indicated generally by the reference character 12. The transformer 10 may of course be of any usual construction but as herein shown includes a body or pack of laminations 13 through and about which the primary and secondary coils are wound as indicated generally at 14 in the drawings. The laminations 13 are generally rectangular in external form, and extend outwardly beyond the outside of the windings 14, and for the dual purpose of holding the laminations 13 together and for securing the transformer in position as for example on the yoke 11, the transformer 10 has a mounting frame 15 disposed in an embracing relationship about three sides of the rectangular pack of laminations. The mounting frame 15 is made from a relatively thin sheet metal that is channel-like in cross section, as shown in Fig. 5 of the drawings, and this channel has flanges 15A formed along its edges so that the channel may snugly embrace the edge portion of the laminations 13, as shown in Fig. 5. The flanges 15A are notched at the 15N at the points where corners are to be formed, thereby to enable the frame 15 to be bent to the generally U-shape form as will be evident in Fig. 1 of the drawings, and the three-sided mounting frame 15 that is thus afforded is disposed in an embracing relationship with respect to the laminations so that the channel form of the frame embraces three sides of the pack 13 of laminations. At the ends of the frame, the channel member extends beyond the face or edge 13B of the laminations to thereby provide ears 15E, and the end portions of the flanges 15A are in each end cut away as in 15C so as to simplify the use of the ears 15E in the mounting operation.

In accordance with standard practice in the art, the ears 15E have transverse slots 20 formed therein so that these slots are disposed with the lower edges 20L thereof disposed somewhat below the lower edge surface 13B of the laminations. In the past the slots 20 have been utilized to receive fastening ears or lugs that were integral with a fixed or stationary member upon which the transformer was to be mounted, and such lugs were, of course, so spaced that in order to engage the lugs with the slots 20 of the mounting frame of the transformer, it has been necessary to bend one or both of the side elements of the frame 15 in an outward direction away from the laminations of the transformer. Thus, these side members of the frame 15 have been bent outwardly along the lines or pivots 15P in an amount sufficient to enable the transformer to be moved into position with the mounting lugs in alignment with the slots 20, after which the side members of the frame have been bent back into position so that the mounting lugs project through the slots 20, and the lugs were thereafter bent so as to hold the side members of the frame 15 in engagement with the mounting lugs.

The construction of the transformer 10 and the mounting frame 15 as hereinabove described has been standard in the transformer industry for many years, and during this time it has been recognized that the separation of the side members of the channel from the laminations in the course of the mounting operation constituted an

objectionable practice because of the tendency to alter the electrical characteristics of the transformer. One factor in altering the electric characteristics has been the release of the laminations 13 which are held together by the flanges 15A of the frame, while another factor has been the change in the relationship of the web of the channel with respect to the edges of the laminations.

Under the present invention, the transformer 10 of the aforesaid standard construction is mounted in position on a magnetic yoke 11 or the like without the necessity for separating or otherwise disturbing the side members of the frame 15. In accomplishing this advantageous result, a mounting plate 25 made from metal and substantially rectangular in form is secured as by spot welding at 25A to the side surface of the yoke 11. The mounting plate 25 has end edge surfaces 25E that are spaced apart in an amount equal to the space between the inner surfaces of the ears 15E, and on each end of the mounting plate 25 a pair of spaced mounting lugs 25L is provided so as to project endwise from the end edge 25E of the plate. The lugs 25L are spaced apart in a distance that is substantially equal to the width of the ears 15E of the mounting frame so that the ears 25E may be moved downwardly, as viewed in Fig. 2, into the spaces between the pairs of ears 25L. When this is done, the inner faces of the ears 15E are disposed in abutment with the end surfaces 25E of the mounting plate 25, while the lugs 25L extend past the opposite edge surfaces of the ears 15E. This preliminary assembly operation is, of course, performed without disturbing the relationship of the side members of the frame 15 with respect to the laminations 13, and hence the electrical characteristics of the transformer are not disturbed in any way.

After the aforesaid preliminary operation has been performed, the lugs 25L and the ears 15E are interlocked so as to hold the transformer in position on the mounting plate 25. In this connection, it should be noted that the formation of the slot 20 in the ear 15E affords a transverse securing bar 20B disposed between the edge 20L of the slot 20 and the lower end of the ear 15E, and this mounting bar is utilized in securing the transformer 10 in position. Thus, the securing bar 20B is bent inwardly to the arcuate form shown in Figs. 1, 3 and 4 so that the upper edge 20L of the bar 20B is disposed beneath and in abutment with the lower face of the mounting plate 25. The lower face 13B of the laminations is, of course, in abutment with the upper face of the mounting plate 25, so that vertical movements of the transformer 10, as viewed in Fig. 1, will be effectually prevented. The lugs 25L are also bent into an engaging relation as will be evident in Figs. 1, 3 and 4, and in this operation the lugs 25L at each end of the plate 25 are bent inwardly so as to overlie the outer faces of the ears 15E. This prevents movement or displacement of the side members of the frame 15 in an outward direction away from the end edges 25E of the mounting plate. Hence, the lugs 25L insure that the securing bars 20B will be held in their interlocked position beneath the lower face of the mounting plate 25. It should be observed that the bending of the securing bar 20B to its arcuate form tends to draw the side edges of the ear 15E together, as will be evident in Fig. 3 of the drawings, and because of this, it is preferable to perform the bending operation upon the bars 20B either prior to or simultaneously with the clinch-

ing of the lugs 25L, for by such procedure the engagement of the lugs 25L firmly with the side edges of the ears 15E is assured.

From the foregoing description it will be evident that the present invention materially simplifies the mounting of electrical transformers in fixed positions on loud speakers or the like, and it will also be clear that the mounting of the transformer is accomplished under the present invention without disturbance of the electrical characteristics of the transformer. The mounting of the transformer under the present invention is also advantageous in that the mounting operations are simplified and may be more readily performed by purely mechanical means.

Thus, while I have illustrated and described the preferred embodiment of my invention, it is to be understood that it is capable of variation and modification and I, therefore, do not wish to be limited to the precise details set forth, but desire to avail myself of such changes and alterations which fall within the purview of the following claims.

I claim:

1. In a transformer mounting, a transformer having rectangular laminations with exposed edges, a three sided mounting frame of channel-shaped cross section embracing three sides of the exposed laminations and embodying securing ears at the ends of the frame extending beyond the fourth side edge of said laminations, said securing ears having transverse slots formed therein so as to define transverse securing bars at the ends of said ears, a mounting plate having a pair of spaced lugs formed at each end thereof, said transformer being disposed on said plate with said fourth side edge of said laminations abutting one face of said plate and with the ears of said frame extending respectively between the pairs of lugs at opposite ends of said plate, said lugs being bent inwardly toward each other and over the related ears to hold the same against the ends of said plate and said securing bars being bent arcuately beneath the opposite face of said plate to hold said ears in position between said lugs.

2. In a transformer mounting, a transformer having rectangular laminations with exposed edges, a three sided mounting frame of channel-shaped cross section embracing three sides of the exposed laminations and embodying securing ears at the ends of the frame extending beyond the fourth side edge of said laminations, said securing ears having transverse slots formed therein so as to define transverse securing bars at the ends of said ears, a mounting plate the opposite ends of which are spaced apart a distance equal to the length of said fourth side of said laminations and said plate having a pair of spaced lugs formed at each end thereof with the lugs of each pair spaced apart a distance equal to the width of said ears, said transformer being disposed on said plate with said fourth side edge of said laminations abutting one face of said plate and with the ears of said frame extending respectively between the pairs of lugs at opposite ends of said plate, said lugs being bent inwardly toward each other and over the related ears to hold the same against the ends of said plate and said securing

bars being bent arcuately beneath the opposite face of said plate to hold said ears in position between said lugs.

3. In a transformer mounting, a transformer having rectangular laminations with side edges and having mounting means thereon including securing ears disposed at the ends of and extending beyond one side edge of said laminations, said securing ears having transverse slots formed therein so as to define transverse securing bars at the ends of said ears, a mounting plate having a pair of spaced lugs formed at each end thereof, said transformer being disposed on said plate with said side edge of said laminations abutting one face of said plate and with the ears of said frame extending respectively between the pairs of lugs at opposite ends of said plate, said lugs being bent inwardly toward each other and over the related ears to hold the same against the ends of said plate and said securing bars being bent arcuately beneath the opposite face of said plate to hold said ears in position between said lugs.

4. In a transformer mounting, a transformer having rectangular laminations with exposed edges, a three sided mounting frame of channel-shaped cross section embracing three sides of the exposed laminations and embodying securing ears at the ends of the frame extending beyond the fourth side edge of said laminations, a mounting plate having a pair of spaced lugs formed at each end thereof, said transformer being disposed on said plate with said fourth side edge of said laminations abutting one face of said plate and with the ears of said frame extending respectively between the pairs of lugs at opposite ends of said plate, said lugs being bent inwardly toward each other and over the related ears to hold the same against the ends of said plate and said ears having portions thereof bent into position beneath the opposite face of said plate to hold said ears in position between said lugs.

5. In a transformer mounting, a transformer having laminations with exposed side edges and having spaced securing ears extending beyond one side edge of the laminations, a mounting plate having a pair of spaced lugs formed at each end thereof, said transformer being disposed on said plate with said one side edge of said laminations abutting one face of said plate and with said ears extending respectively between the pairs of lugs at opposite ends of said plate, said lugs being bent inwardly toward each other and over the related ears to hold the same against the ends of said plate and portions of said ears being bent beneath the opposite face of said plate to hold said ears in position between said lugs.
